No. 37,409.

Patented April 18, 1905.

UNITED STATES PATENT OFFICE.

WILLIAM GRAY, OF AMESBURY, MASSACHUSETTS.

DESIGN FOR A LAMP.

SPECIFICATION forming part of Design No. 37,409, dated April 18, 1905.

Application filed February 11, 1905. Serial No. 245,326. Term of patent 7 years.

To all whom it may concern:

Be it known that I, WILLIAM GRAY, a citizen of the United States, residing at Amesbury, in the county of Essex, State of Massachusetts, have invented a new, original, and ornamental Design for Lamps, of which the following is a specification, reference being had to the accompanying drawings, forming part thereof.

Figure 1 is a perspective view of a lamp,

showing my design. Fig. 2 is a front view in elevation.

I claim—

The ornamental design for a lamp, as shown.

WILLIAM GRAY.

Witnesses:

A. P. LANE,

F. E. STEPHAN.
